FOOD CONTAINER LID

William D. Taylor, Wooster, Ohio, assignor to Rubbermaid Incorporated

Filed Sept. 27, 1972, Ser. No. 294,264

Term of patent 7 years

Int. Cl. D7—02

U.S. Cl. D7—131

FIG. 1

FIG. 2

FIG. 3

FIG. 1 is a top plan view of a food container lid embodying my new design.

FIG. 2 is a side elevation thereof.

FIG. 3 is a sectional view on line 3—3 of FIG. 1.

The bottom is plain and unornamented.

I claim:

The ornamental design for a food container lid, as shown and described.
